UNITED STATES PATENT OFFICE

2,312,390

AUTOMOTIVE CRAWLER VEHICLE WITH A SCRAPER BOWL HAVING A BULLDOZER BLADE

Hugo Cordes, Hamburg-Altona, Germany; vested in the Alien Property Custodian

Original application February 12, 1940, Serial No. 318,597. Divided and this application October 23, 1940, Serial No. 362,466. In Germany February 13, 1939

6 Claims. (Cl. 37—124)

Examples of automotive crawler vehicles having scraper bowl and vehicle frame rigidly connected are already known, where the scraper bowl is movably positioned between the crawlers, yet where neither a special closure mechanism for the bowl nor a bulldozer blade is provided.

This invention relates to subject matter divided out of a co-pending application filed Feb. 12, 1940, Serial No. 318,597.

Moreover it is known, with dirt-moving machinery on wheels without crawlers to close the scraper bowl by a front apron. This front apron can also be formed like a clam shell and can be of any capacity in relation to the capacity of the scraper bowl.

According to the invention an automotive crawler vehicle having scraper bowl and frame rigidly connected and the bowl movably positioned between the crawlers is fitted with a front apron, which is also adapted to swing in a vertical plane and by which the scraper bowl can be closed off. As it is a drawback with crawler vehicles thus constructed that the cutting edge is not so long as the width of the vehicle, the front apron is, according to the invention, connected with a bulldozer blade. This blade is longer than the total width of the crawler vehicle and permits deep incisions to be made by the machine. The blade can be firmly or detachably secured to the front apron, or movably in such a way that the blade can be turned about an approximately vertical axis into a position crosswise or inclined to the direction of travel.

In addition, according to the invention, the free edge of the apron can pass the cutting edge of the scraper bowl. Thus it is possible either to dig into the ground with the cutting edge of the bowl, thus filling the bowl, and to carry the dirt in the bowl over a wide distance, or to use the bulldozer blade for making incisions and for planing wide surfaces.

The attached drawings show the invention in two examples, where in one instance the bulldozer blade is rigidly secured to the apron and in the other instance movably connected in such a way that it can be turned into its working position crosswise or inclined to the direction of travel about an approximately vertical axis.

Fig. 1 shows the vehicle in transporting position with the apron closed in longitudinal section.

Fig. 2 is a plan view of same.

Fig. 3 shows the vehicle in digging position in longitudinal section.

Fig. 4 shows the vehicle in dumping position also in longitudinal section.

Fig. 5 shows the vehicle with the blade lowered (levelling position) in longitudinal section.

5 The bowl 1 (Figs. 1 and 2) is rigidly secured to the frame 2, which carries the motor 3 and the sprocket wheel drive 4. It has the cutting edge 5 and is movably mounted by means of the horizontal shaft 6 upon the crawler frames 7 and 29 with the crawlers 8 and with truck rollers 9. The cylinders 10 are mounted on frame 2, their pistons 11 acting by means of push rods 12 on levers 13, which are secured to the crawler frames 7 and 29. The cutting edge 5 will be 10 brought to the desired level by inclining the whole vehicle frame 2 through the action of cylinders 10. The apron 14, which is pivoted at 15 on the bowl 1 is moved by cylinders 16 pivotally joined to the bowl. The cutting edge 17 of the apron 14 comes near the cutting edge 5 and more or less closes the bowl. To apron 14 the blade 18 is either rigidly secured (Figs. 3 and 4) or movably held in an approximately vertical axis 19 (Figs. 1, 2 and 5), by an intermediary piece 20, which pivots about the horizontal axis 21 on the apron 14 and has its incline determined by the variable length of links 22. By intermediary pieces 23 and 24 of variable length the blade can be set at various angular 15 positions to the driving directions (see dotted lines in Fig. 2).

20 The digging work (Fig. 3) being finished, in order to avoid loss of excavated material, the apron 14 will be closed, while the cutting edge 5 is being raised. As the blade 18 on apron 14 may hit on obstacles, and the bowl could not be closed then, the blade 18 must be positioned as high as possible on apron 14 that it does not touch the ground too early when the apron is lowered. Hence it follows that for the bulldozing position (Fig. 5) the apron 14 must be adapted to be lowered beneath the transporting position (Fig. 1), in order to have the cutting edge 5 of the bowl high enough over the ground when working with the blade, especially when working above the travelling plane. According to the invention the edge 17 of the apron 14 can pass the cutting edge 5 until apron 14 hits the stops 25 on the bowl 1. During this bulldozing work the blade is lowered or raised also by inclining the frame by means of the cylinders 10.

25 The bowl (Fig. 4) is emptied by cylinder 26 on frame 2, which pushes the rear portion 28, turnable about axis 27, in a forward direction.

30 Motor 3 is coupled over gear wheels with the

sprocket drive wheels 4 and drives a pump for pressure fluid or compressed air (not shown).

Having thus described my invention, what I claim is:

1. An automotive crawler vehicle with a scraper bowl having means for dumping the load, the bowl being movably supported on said vehicle and with its cutting edge adapted to be lowered below the ground level characterized thereby that the bowl is provided with a movable power actuated apron, by which said bowl can be closed at the cutting edge, a bulldozer blade being attached to the movable apron.

2. An automotive crawler vehicle with a scraper bowl according to claim 1, characterized thereby that the bulldozer blade is detachably secured to the movable apron and in such a way, that it can be turned about an approximately vertical axis.

3. In an earth handling vehicle, a frame, a scoop bowl mounted on said frame and having a bottom, a bull-dozer blade having arms extending rearwardly of the blade and pivoted to the bowl, means to swing the arms to raise and lower the blade, and an apron carried by said

arms and forming a continuation of the bowl bottom upon the blade being lowered whereby to prevent entry of dirt into the bowl during use of the blade and loss of the dirt during transportation.

4. The vehicle of claim 3 wherein the arms are connected at their forward ends by a cross-bar and the apron extends rearwardly from the bottom of the cross-bar and spans the space between the arms.

5. The vehicle of claim 3 wherein the apron extends rearwardly from the blade on a line spaced above its lower edge and spans the space between the arms.

6. A vehicle provided with a scoop bowl having means for dumping the load, the scoop bowl being movably supported in such a manner that its cutting edge is adapted to be lowered below the ground level; said vehicle being characterized in that the scoop bowl is provided with a movable power actuated apron capable of closing said scoop bowl at the cutting edge, one of the walls of said apron being at the same time shaped in the form of a bulldozer blade.

HUGO CORDES.
